PRODUCTION OF CEMENT

Johan Norvig, Hartsdale, N. Y., assignor to International Cement Corporation, New York, N. Y., a corporation of Maine

Application May 2, 1930, Serial No. 449,117

8 Claims. (Cl. 263—32)

This invention relates to the production of cement and more particularly to the cooling of the cement clinkers after they leave the firing kiln.

5 In the production of cement it has been the practice to cool the clinkers produced in the kiln by merely dumping them into bins or piles and allowing the mass to cool slowly by radiation. Such a procedure is necessarily slow, and it requires a great deal of space and results in a considerable loss of heat units.

In order to avoid these disadvantages, attempts have been made to artificially cool the clinkers, such as by cascading them through vertical stationary towers in the presence of a counter-current flow of cooling air, or by passing them through rotary coolers provided with vanes to lift the clinkers and cascade them as they are progressed through the kiln in contact with a counter-current stream of air. The apparatus required for such operations is very voluminous and the quantity of air necessary to accomplish the cooling is greater than that needed for the combustion of the fuel in the kiln. Furthermore, the 25 air temperature, resulting from the cooling of the clinkers, is not raised sufficiently high to assist greatly in the combustion of fuel. Also the air leaving this type of cooler is laden with dust particles which interfere with the practical operation 30 of the kiln and constitute a nuisance if not caught in dust collectors.

It is an object of my invention to avoid the above difficulties by providing an improved method and means for cooling the clinkers. It is 35 a further object of the invention to improve the characteristics of the clinkers resulting from the cooling operation. Another object is to provide quicker and more effective cooling with a minimum amount of air and to thereby obtain a greater concentration of heat units in the pre-heated air supplied for combustion in the kiln. A further object is to reduce the quantity of dust in the preheated air supplied to the kiln. Another object is to provide an apparatus for accomplishing such results. Other objects will become apparent.

I have found that by cooling the clinkers very quickly after they leave the kiln, the grindability 50 of the clinkers will be greatly improved. To accomplish this the clinkers are subjected to concentrated cooling by passing the cooling air through a moving grate or grid upon which they are supported.

In describing my invention reference will be 55 made to the drawings in which Figure 1 is a dia-

grammatic representation of a side elevation of an embodiment of my improved cooler with the forward portion shown in section. Figures 2 and 3 are sections taken on the lines 2—2 and 3—3, respectively, of Figure 1. Figure 4 is a fractional view similar to Figure 1 showing the hopper filled with clinker.

The numeral 1 indicates a cement kiln of the rotary type. The lower end of the kiln is surrounded by an insulated kiln hood 2 which is connected with a collecting chamber 3. An opening 4 is provided in the lower portion of one side of the collecting chamber, through which the hot clinkers run by gravity onto a moving chain grate 5. The chain grate moves continuously around 15 the wheels 6, 6 as indicated by the arrows and the clinkers are carried by the grate toward the hopper 7. The level of the clinkers upon the grate may be regulated by a guide lip 8 at the outlet from the collecting chamber (as illustrated in 20 Figure 4) or the pile of clinkers may be allowed to take their natural slope after adjusting the dimensions and speed of the grate to take the normal output from the kiln.

The first portion of the chain grate 5 is surrounded by a hot air chamber 9 and the cooling air is forced into this chamber through a flue 10 connected with a pressure blower 11. The outlet from the chamber 9 is connected through a flue 12 to the rotary kiln at a point adjacent the 25 fuel pipe 13 for supplying powered coal, oil or gas.

A second hot air chamber 14 is built around the remaining portion of the upper surface of the moving grate 5 and cooling air may be drawn through this portion of the grate, through the 30 flue 15 and into the dust collector 16, by the suction fan 17.

In operating my improved cooler, the clinkers from the rotary kiln 1 fall into the collecting and distributing chamber 3 and form a pile 18 at the bottom which takes a natural slope and protects the bottom of the chamber from the contact of hot clinkers. The clinkers drop onto the moving grate 5 and spread over the surface of the grate to form a smooth layer. This layer is continuously progressed with the grate 5 through the hot air chamber 9 where it is quickly cooled. The highly heated air from this portion of the cooler is lead to the kiln 1 at a point adjacent the fuel pipe and is utilized in the combustion of the fuel.

The bed of clinkers is then conveyed through the second cooling chamber where a second draft of cooling air is passed through it. The air from this cooling step may be conducted to the dust collector and thereafter used for heating, drying

or any other desired use. The cooled clinkers may then be drawn off through the hopper 7 and disposed of as desired.

If preferred the second cooling chamber 14 may also be connected with a pressure blower and the cooling air may be forced through the grate and clinkers. Also the current of air may be reversed and drawn or forced through the clinkers and grate in a downwardly direction. It is also apparent that the cooling may be accomplished in a single chamber extending over the entire length of the grate and the air may be drawn or forced through the clinkers and grate within this chamber after which a portion or all of the preheated air may be lead to the kiln hood through a suitable flue. The flow of air through the first cooling chamber may also be in a downwardly direction, if such operation is preferred.

By following the procedure described the clinkers may be cooled from the temperature of the kiln down to 200-400° F. or lower in about 10 to 15 minutes. The clinkers resulting from this rapid cooling is of such a structure that they may be more easily ground or broken in the subsequent treatment to produce the finished cement.

It is apparent that many other forms of apparatus may be used in place of that described in the illustrations and it is not intended to hereby restrict the invention to the particular embodiment shown. For example, the moving grate may be replaced by moving cars having perforated bottoms and the movement of the grate or cars may be intermittent rather than continuous. The improved clinker cooler may also be used with other types of cement burning apparatus, such as a vertical kiln or a chain kiln.

The preheated air led to the kiln may, of course, be cleared of dust particles by passing it through a cyclone or other dust separator if that is considered necessary.

Since the bed of clinkers is stationary relative to the grate the cooling will be accomplished with the minimum dusting. The concentration of the cooling and the intimate contact of the cooling medium with the clinkers will provide the maximum efficiency of operation. The passage of the cooling air through the grates and hot clinkers will protect the grades from the heat given off by the hot clinkers.

50 What I claim is:

1. In an apparatus of the class described, a kiln, a hood surrounding the outlet end of said kiln, a perforated longitudinally progressing conveyor in communication with said hood, an enclosure surrounding the receiving end portion of said conveyor, means for forcing air upwardly through the portion of said conveyor within the enclosure, and means for conducting air from said enclosure to the kiln at a position adjacent the fuel feed.

2. In an apparatus of the class described, a kiln, a perforated longitudinally progressing conveyor communicating at its receiving end with the outlet from the kiln, a hood surrounding the receiving end portion of said conveyor, means for passing air through the clinkers upon the portion of the conveyor within said hood, a conduit for conducting air from the hood to the kiln, a second hood surrounding a subsequent portion of the conveyor and means for causing air to pass through the conveyor in said second hood and through a dust separator connected therewith.

3. Apparatus for the manufacture and treatment of cement clinkers comprising, in combination, a primary combustion chamber wherein cement clinkers are formed, a clinker treatment chamber arranged at one end to receive a continuous discharge of highly heated cement clinker from the combustion chamber, means for advancing said clinkers as a continuous stream through said treatment chamber from an intake at one end thereof to a discharge at the opposite end, 10 means for directing an air draft through said advancing stream of clinkers within the treatment chamber, means separating the air space within the treatment chamber from the primary combustion chamber to prevent flow of air from 15 the treatment chamber into the primary combustion chamber through the clinker passageway, means separating the air space within the treatment chamber into two compartments, and means for taking the air away from said compartments 20 separately.

4. An apparatus of the class described, comprising a kiln, a perforated longitudinally progressing conveyor grate communicating with said kiln for moving the hot clinkers from the outlet 25 of the kiln, a hood surrounding the first portion of said conveyor, said hood being connected by a flue, separate from the kiln discharge, to the kiln and means for passing air through the bed of clinkers upon the grate and through the flue into 30 the kiln.

5. An apparatus of the class described, comprising a kiln, a perforated longitudinally progressing conveyor grate communicating with said kiln for moving the hot clinkers from the outlet of the 35 kiln, a hood surrounding the first portion of said conveyor and communicating with the kiln, a second hood surrounding another portion of the conveyor and communicating with an outlet flue and means for passing air through the bed of 40 clinkers on the portions of the conveyor within said hoods.

6. In an apparatus of the class described, a kiln, a conveyor communicating with the outlet of the kiln and adapted to receive hot clinkers from 45 the kiln and convey them in a relatively thin layer, an enclosure surrounding the receiving end portion of said conveyor, means for causing air to pass through the portion of said layer of hot clinkers within the enclosure, means for conducting said air to the kiln and means for passing a separate quantity of air through the layer of clinkers after it leaves the said enclosure.

7. An apparatus as defined in claim 6 in which the air from the enclosure is fed to the kiln at 55 a point adjacent the fuel inlet for the kiln.

8. In an apparatus of the class defined, a kiln, a conveyor communicating with the outlet of the said kiln and adapted to receive hot clinkers therefrom and convey them in a relatively thin 60 layer, separate enclosures for the first and subsequent portions of said conveyor, means for causing air to pass through the layer of clinkers in said enclosures, means for conducting the air from the first of said enclosures to the kiln for 65 combustion therein, and means for separately disposing of the air from the other of said enclosures.

JOHAN NORVIG.
